UNITED STATES PATENT OFFICE.

VICTOR H. M. ROEHRICH, OF ST. PAUL, MINNESOTA.

COMBUSTION-PAN FOR BOMB-CALORIMETERS.

1,289,918.

Specification of Letters Patent. Patented Dec. 31, 1918.

Application filed July 27, 1914, Serial No. 853,530. Renewed April 3, 1916. Serial No. 88,702.

To all whom it may concern:

Be it known that I, VICTOR H. M. ROEHRICH, a citizen of the United States, residing at St. Paul, in the county of Ramsey and

5 State of Minnesota, have invented a new and useful Improvement in Combustion-Pans for Bomb-Calorimeters, of which the following is a specification.

In determining the thermo units liberated 10 by the combustion of any material by the use of an oxygen bomb calorimeter, it has been customary to use a fuse heated by an electric current in order to ignite the material in the oxygen filled bomb. This fuse in the 15 form of a wire has usually been placed in the mass of combustible material where the heat is so intense as to melt it, making it impossible to use the fuse wire for more than one determination even if a very heavy 20 platinum wire, say No. 16 B. and S. gage were used. To make it possible to use the same wire repeatedly, and to thus save expense and time is the primary object of this invention.

25 In the accompanying drawing forming part of this specification, Figure 1 is a vertical central section of an ordinary bomb calorimeter constructed with my invention, and Fig. 2 is a perspective of the combustion 30 pan removed from the calorimeter.

In the drawing A indicates the ordinary bomb calorimeter having a receptacle B and a removable collar C, which serves to clamp a cover D, tightly over the receptacle to 35 complete a gas tight chamber within. In the cover D is the usual gas duct E, which is adapted to be closed by the usual valve F, which forms one terminal of an electric circuit passing through the structure. Imme- 40 diately adjacent the valve in the cover is a terminal piece G, forming the other side of the circuit and secured to the cover by a bolt H, which is suitably insulated by the parts I from the cover. This bolt has formed 45 integral therewith a depending rod J, which is bent into a loop at its lower end for the purpose of receiving and holding the combustion pan or capsule K, in which the fuel to be tested is placed. This pan is usually 50 made out of platinum so as to withstand high temperatures, and at one side is ar- ranged with a small bay L, containing a groove, depression or channel, which com- 55 municates with the main body of the pan. In this bay is placed a wire fuse M, of short length and of about #28 gage or other suit-

able size, of platinum or other suitable material. One end of the wire fuse is fastened to the pan by a small bolt N or other suitable means and its opposite end is loosely at- 60 tached to a support O, which is an electrical conductor secured to the cover D and completes the electric circuit between the terminals, through the fuse and the pan, it being noted that the pan is held in a support 65 which forms part of the electric circuit. The wire fuse is bent downwardly between its ends, so as to dip into the combustible material which is placed in the pan and ex- tends into the bay L. 70

In operation the greater part of the combustible material to be tested is placed in the body of the pan and a small portion ex- 75 tended into the bay covering the fuse wire. The pan is then placed in the holder J and the fuse adjusted in contact with the con- ductor support O. The cover D is then placed on receptacle A and the collar C screwed down upon the receptacle until the cover is fastened tightly to form a gas tight 80 chamber within the receptacle and cover. After filling the calorimeter bomb with oxy- gen and preparing for making the test in the usual manner, the electric circuit is closed for a few seconds, and then again opened. 85 The heated fuse wire ignites the material covering it, and the combustion spreads igniting the bulk of the sample. The heat de- 90 veloped near the fuse wire is relatively small, so that the wire remains to be used repeat- edly and is not destroyed as in prior de- 95 vices. By this arrangement the fuse wire is protected from the relatively intense heat to which it would be exposed if placed in the main portion of the sample as heretofore. 95

In accordance with the patent statutes I have described the principles of operation of my invention together with the apparatus which I now consider to represent the best embodiment thereof, but I desire to have it 100 understood that the construction shown is only illustrative and that the invention can be carried out by other means and applied to uses other than those above set forth within the scope of the following claims. 105

Having described my invention, what I claim as new and desire to protect by Let- 110 ters Patent is:—

1. In combination with a bomb calo- rimeter, a combustion pan supported therein 110 and formed with a bay, an electric fuse pro- jecting in that part of the material to be

tested contained in said bay and adapted by the passage of an electric current there-through to ignite the fuel contained in the bay and causing the body portion of the fuel to be consumed without melting said fuse.

2. A calorimeter having a combustion chamber adapted to be connected with one side of an electric circuit, a combustion pan support in said chamber connected with the other side of an electric circuit and insulated from the structure of said chamber, a combustion pan carried by said support, said pan being formed with a bay, a wire fuse attached to said pan and dipping down into said bay in position to ignite the fuel contained in said pan and a conductor supporting the free end of said fuse above said pan and connected with the structure of said chamber to complete an electric circuit passing between said support and the structure of said chamber and through said fuse.

3. In combination with a bomb calorimeter, a combustion pan for holding material to be tested having a channel leading from its body and means associated with said channel for igniting the contents of the channel and pan and causing the com-

bustion of the material being tested without damaging said igniting means.

4. In combination with a bomb calorimeter, a combustion pan having a small adjacent channel holding a small proportion of the material being tested in said pan, and means in said channel for igniting and causing the combustion of the contents of said channel and the body of said pan, without exposing said igniting means to the damaging heat effects of the contents of the body of said pan.

5. A combustion pan for calorimeters having a connection arranged to hold a small proportion of the body of the material to be tested away from the damaging heat effects of said body, an igniter arranged in contact with the material held in said connection and electrical means for heating said igniter while it is in said connection.

In testimony whereof, I have signed my name to this specification, in the presence of two subscribing witnesses.

VICTOR H. M. ROEHRICH.
